JAY GOULD COUTANT, OF NEW YORK, N. Y., ASSIGNOR, BY MESNE ASSIGNMENTS, TO
EDWARD J. FRANKLIN, OF SALT LAKE CITY, UTAH

STEAM GENERATOR

Original application filed October 5, 1925, Serial No. 60,435, and in France October 7, 1924. Divided and
this application filed May 8, 1931. Serial No. 535,922.

This invention relates to steam generators and particularly to a certain combination of water tube boiler and furnace. The illustrated embodiment of the invention indicates a furnace fired by pulverized coal.

The general object of the invention is to improve the construction and operation of boiler furnaces, and a particular object is to provide a construction of water tube boiler and furnace having improved provision for the collection and disposal of ashes or solid material which may be carried from the combustion chamber into the boiler. Other and further objects and advantages will be pointed out in the hereinafter following specification or will be apparent to those skilled in the subject. To the attainment of such objects and advantages the present invention consists in the novel steam generator or boiler and furnace and the novel features of operation, construction, combination and detail herein illustrated or described.

In the accompanying drawing, Figure 1 is a vertical section of a water tube boiler with furnace, embodying the principles of the invention, and Fig. 2 is a detail section taken on either of the lines 2-2 of Fig. 2.

These figures correspond with the figures of the drawings of my French patent application filed October 7, 1924, Serial No. 193,631, which has subsequently resulted in the grant of French Patent No. 600,505, and correspond with Figs. 1 and 2 of my copending U. S. application filed October 5, 1925, Serial No. 60,435, of which U. S. application the present application is a division.

As in said copending application, the combustion chamber 10 may be considered as comprising a lower or high temperature zone 11 and an upper or temperature reducing zone 12. The right side of Fig. 1 will be considered the front of the furnace. The chamber 10 is bounded by an upper front wall 14 and a continuation 15 thereof constituting the lower front wall. The combustion chamber is further bounded by rear side wall 16 and opposite end walls 17, all of which may be composed of suitable high refractory material. The floor or bottom 18 may be constructed of similar material, and

its opposite sides are shown as inclined to an ash exit 19. These features are illustrative, the present invention is not directed to them but rather to the features later described, and the type of combustion chamber and mode of combustion may be varied.

The boiler 21 is of the water tube type having a bank of tubes 22, a first baffle 23, and a second baffle 24, directing the products of combustion through the first, second and third passes of the boiler. The tubes 22 are fed through rear lower headers 22^a and deliver steam by upper front headers 22^b, the lower rear headers being shown with the usual drum 22^c in which are collected and from which are removed by suitable draining connections solid matters or sediment.

Spaced somewhat below the boiler tubes 22 is shown a supplementary series of water tubes 25 constituting a slag screen, tending to reduce preliminarily the temperature and eliminate passage of fused ash and formation of slag on the boiler tubes. The gas exit from the furnace is shown as an escape flue 26.

When pulverized coal is burned in the chamber 10 it is preferably projected inwardly on a downward slant, so as to distribute and scatter the fuel, which substantially instantaneously takes part in the combustion. A series of fuel injecting burners 27 is indicated extending across the front wall 15 of the furnace, fed by pipe 28, for example from a pulverizing machine 29. Supplemental air for combustion may be introduced through a series of rear nozzles 34 supplied by pipes 35 which may conduct heated atmospheric air to the nozzles, received through pipes 36 leading from a jacket space 37 arranged between the outer shell 38 and an inner wall 39 of the furnace. The further details of combustion may be ascertained by reference to said copending application.

Out of the gases passing from the second to the third pass of the boiler will be deposited or settled fly ash, flue dust or other solid materials carried by the gases, and these solid matters are disposed of by the present invention in the following manner.

The wall 39 already referred to, is shown as enclosing an ash hopper 40, the wall forming the rear wall of the hopper. The ashes precipitating into the hopper 40 from the boiler tube spaces are shown carried downwardly through an opening in the ash pocket and thence by a chute 41 to a convenient point of delivery or disposal.

While the lower zone 11 of the combustion space is preferably kept at top temperature, the upper zone 12 is preferably cooled. This is shown as effected herein by means of water cooled walls around the upper part of the combustion chamber. Thus a series or row of vertical water tubes 50 is shown arranged across the end walls of the space 12. A similar series of water tubes 51 is shown extending across the rear wall of the space. The heat received in the tubes 50 and 51 causes substantial and useful evaporation which, as the tubes are in circulation with the boiler, greatly increases the effective direct heating surface and evaporative power of the boiler.

The end wall tubes 50 are shown as connected by lower and upper headers 52 and 53, in communication with the boiler in a usual manner. The rear wall tubes 51 are shown connected by a lower header 54, while the upper ends of the tubes 51 may be continuations of the tubes 25 already mentioned as serving the function of a water screen or slag screen between the combustion chamber and the boiler. The tubes 51 thus deliver ascendingly into the tubes 25 and these in turn into one of the drums of the boiler. As the slag screen tubes 25 should be spaced relatively widely apart, a header 55 is shown between them and the rear wall tubes 51.

Preferably the water tubes 50 and 51 surrounding the upper zone or space 12 are arranged in front of refractory walls or backings. Thus behind each series of tubes is shown a brick wall 56. While this might be slightly spaced outwardly from the tubes it is preferably closely adjacent to the tubes, and a construction is preferred, as shown, wherein portions 57 of the refractory material project forwardly into the spaces between the tubes, substantially in the manner shown in the sectional view Fig. 2. These portions or lugs 57 may be produced by using refractory bricks of T-shape. Preferably plastic or other blocks or bricks of high refractory and heat conductive properties are employed. A closed water-cooled wall comprising the tubes and the closing means or refractory is thus afforded, with the tubes preferably exposed to the combustion. Due to the cooling of gases afforded by the water tubes 50 and 51 the refractory material is not exposed to the deposit of liquid ash, and a refractory may be selected to which such ash will not adhere. In case access may be desired to the water tubes 50 and 51 a series

of openings or doors 58 may be provided in the adjacent refractory walls, for inspection, removal of slag, etc.

The general combustion operation is described fully in the copending application. The problem of handling ashes is substantially reduced by the present improvement, since 30% or more of the total ash production may be collected and disposed of through the hopper 40, bounded at the rear by the wall 39 and at the front by the rear wall 56 of the combustion space 12, which wall 56 is seen to be extended upwardly at a slant, with an extension thereabove forming a continuation of the first boiler baffle wall 23. Other ashes will of course be collected on the floor and disposed of through the exit 19.

Attention is directed to the feature of the over-hanging or inwardly inclined rear wall of the upper part of the combustion space, consisting of the water tubes 51 and the refractory backing 56, constituting a continuation of the first baffle 23. This structure gives an advantageous course to the flames and permits the ash space or pocket 40 to be maintained exterior to the inclined wall, whereby ashes can be collected in the pocket and suitably delivered therefrom, as by the chute 41 as already explained.

The water tubes 51 which face the rear wall 56 are in direct connection by the header 55 with the tubes 25 of the slag screen, these combined sets of tubes forming a separate circulating system from the boiler proper, being fed by independent connections 51^a from the main boiler drum 21^a and delivering steam independently by connection 25^a to a secondary drum 21^b of the boiler. This improves the circulation and gives a more effective operation of the rear wall and slag screen. The end wall tubes 50 also are shown connected to the boiler drum independently of the main boiler tubes. These separate circulating systems carry water at very high temperatures. They carry a small amount of water, but the very hot water offers low resistance to flow, and this increases the rate and effectiveness of the circulation in these tubes, thus affording a high rate of heat absorption per unit of tube area.

While the tubes 51 of the rear wall or bridge 56 are preferably exposed to the fire, their upper header 55 is preferably shielded, as shown, by being located behind the wall, the tubes 51 and 25 passing through the wall. The mud drum 22^c of the boiler also is shielded by the wall 56. Both the drum 22^c and the header 55 are preferably inside of the ash pocket 40, as shown.

For the purpose of the claims the illustrated disclosure may be described as follows. Considering the boiler tubes 22 and the slag screen tubes 25 as cooperating parts of the boiler system, they constitute a plurality of

rows or banks of water tubes above the combustion chamber and connected for circulation of water therethrough. The lowermost row of all of said tubes, namely the row 25, has its rear end portions, namely, the tubes 51, bent, inclined or turned obliquely downwardly and rearwardly, at a greater angle than the tubes 22 and 25, to a position at or adjacent to the rear wall of the combustion chamber and so as to be clear of or separated from the remaining rows 22 of boiler tubes. The disclosure embodies means connecting the lower rear ends of said lowermost row of tubes to the water circulating system, namely by the downcomer 51^a and the header 54, the header being outwards of and protected by the lower rear wall portion 16. The disclosure also embodies inclined refractory baffle means, namely the rear wall 56 extended upwardly into the boiler as baffle 23, the said wall 56 being adjacent to or supported upon the said inclined portions 51 of said tubes, so as to close the spaces between them. Said inclined refractory wall 56 cooperates with the wall 39 to the rear thereof to form the pocket 40 below the rear ends of said remaining tubes 22 of the boiler, such pocket converging downwardly, for collection of ashes or solid material in the pocket, and this pocket has means or an opening in its walls for permitting discharge of ash from said pocket, namely through the chute 41, which may be opened at intervals for discharge and otherwise closed for accumulation of ashes. The inclined rear baffle wall extension 56 is a refractory wall exposed to the combustion in chamber space 12; at its face it is protected by a single row of face tubes 51 and so constitutes a water wall; at its back it encloses the ash receiving pocket 40.

There has thus been described a steam generator of water tube boiler and furnace embodying the principles and attaining the objects of the present invention; but as many matters of operation, construction, combination and detail may be variously modified without departing from the principles of the invention, it is not intended to limit the invention to such matters except to the extent set forth in the appended claims.

What is claimed is:

1. In a water tube boiler, in combination with a furnace having a combustion chamber, a plurality of rows of water tubes above said combustion chamber and connected for circulation of water therethrough, the lowermost row of said tubes having their rear end portions inclined downwardly and rearwardly to a position adjacent the rear wall of the combustion chamber and in such position as to be clear of the remaining rows of tubes, means connecting the rear ends of said lowermost row of tubes to the water circulating system, inclined refractory baffle means supported upon said inclined portions of said

tubes and cooperating with a wall to the rear thereof to form a pocket below said remaining tubes for collection of ashes or solid material, and an opening for permitting discharge of ash from said pocket. 70

2. In a water tube boiler, in combination with a furnace having a combustion chamber, a plurality of rows of inclined water tubes above said combustion chamber and connected for circulation of water therethrough, the lowermost row of said tubes having their rear end portions bent so as to be inclined downwardly at a greater angle to the horizontal than the remaining tubes and said inclined portions extending from a position intermediate the ends of the remaining rows of tubes to a position immediately adjacent the rear wall of the combustion chamber, baffle means of refractory material located above and supported upon said inclined portions of said tubes and cooperating with a wall to the rear thereof to provide a downwardly converging pocket for collection of ashes or solid material, and openable means permitting discharge of material from said pocket. 80

3. In a boiler furnace, a front wall, a rear wall, a substantially unobstructed combustion chamber extending between said front and rear walls, a plurality of rows of water tubes extending above said combustion chamber, the rear portion of the lowermost row of said tubes extending obliquely downwardly to the rear wall of the chamber, a baffle of refractory material supported on said rear portions of said lowermost row of tubes and extending upwardly and forwardly from said rear wall to a position above the combustion chamber and cooperating with a wall to the rear thereof to provide a downwardly converging pocket for collection of ashes or solid material, and means in a wall of the pocket for permitting discharge of material from said pocket. 100

4. In a boiler furnace, a front wall and a rear wall to the combustion chamber, a substantially unobstructed combustion chamber extending between said front and rear walls, a plurality of rows of inclined water tubes extending above said chamber, the tubes in the lowermost row of said tubes having their rear portions bent so as to be inclined downward to the rear at a greater angle than the remaining tubes, said bent portions extending from a position intermediate the ends of the remaining rows of tubes to a position immediately adjacent to the rear wall of the chamber, a refractory baffle supported on said bent portions and extending upwardly and forwardly from said rear wall so as to form a part of the wall of the combustion chamber and to direct the combustion products therefrom into contact with the forward portions of said rows of water tubes and to also cooperate with a wall to the rear of the 110

115

120

125

130

baffle to provide a downwardly converging pocket above said baffle for collection of solid material, and means in a wall of the pocket for permitting discharge of material from said pocket.

5. In a water tube boiler, in combination with a furnace having walls enclosing a combustion chamber, and means for burning injected or fluent fuel therein, a series of rows of water tubes above said combustion chamber and connected for circulation of water therethrough, the lowermost row having their front portions substantially parallel with the remaining tubes and their rear portions substantially inclined downwardly and rearwardly to a position adjacent the rear wall of the chamber and with a connecting header shielded by said wall, means connecting such header to the boiler circulating system to bring water thereto, inclined baffle means substantially in exterior contact with said inclined portions of said tubes, a wall to the rear of said baffle cooperating therewith to form a pocket below the rear portion of said remaining tubes for the collection of ashes or solid material, and a conveying chute arranged for downward delivery of material from said pocket.
- 10 15 20 25

6. A furnace for burning fluent fuel in suspension in air for heating a boiler, comprising walls enclosing a combustion space, means for injecting the fuel and air into the lower portion of the combustion space for combustion therein, one of the walls surrounding the upper part of the combustion space being inclined inwardly to overhang the space, a series of water tubes at the inner face of said inclined wall exposed to direct radiation and connected in circulation with the boiler whereby the evaporation therein supplements that of the boiler, a baffle extending into the boiler as a continuation of said inclined wall, and a wall behind said inclined

wall forming therewith an ash pocket, and said pocket having means for discharging collected ash therefrom.

7. In a water tube boiler furnace, in combination with walls enclosing a combustion chamber and means for burning injected or fluent fuel therein, a series of rows of water tubes above said combustion chamber and connected for circulation of water therethrough, the tubes of the lowermost row having their front portions substantially parallel with the remaining tubes and their rear portions substantially inclined downwardly and rearwardly to a position adjacent the rear wall of the chamber and with a connecting header shielded by said wall, means connecting such header to the boiler circulating system to bring water to such header, as inclined baffle supported adjacently behind said inclined portions of said tubes, a wall to the rear of the baffle and cooperating therewith to form a pocket below the rear portion of said remaining tubes for the collection of ashes or solid material, and means near the lower end of said pocket for removal of material from the pocket.

8. A steam generator comprising a water tube boiler above a furnace, the furnace having an inclined refractory wall below the boiler and overhanging one side of the combustion space, a row of water tubes embodied in and facing the inner side of said inclined wall, and arranged in circulation with the boiler, said inclined wall and row of tubes exposed to the fire, said inclined wall having a baffle extension into the boiler, and the water tubes facing the inner side of the overhanging wall having their upper ends carried through said wall and connected to a common header outside of and shielded by said wall.
